ATTORNEY

UNITED STATES PATENT OFFICE.

JAMES RICHARDSON, OF NEW YORK, N. Y., ASSIGNOR TO HIMSELF AND
FRANK E. HEATH, OF SAME PLACE.

FLYING-MACHINE.

SPECIFICATION forming part of Letters Patent No. 596,231, dated December 28, 1897.

Application filed October 3, 1896. Serial No. 607,747. (No model.)

To all whom it may concern:

Be it known that I, JAMES RICHARDSON, a citizen of the United States, residing at New York, in the county of New York and State 5 of New York, have invented certain new and useful Improvements in Flying Machinery, of which the following is a full, clear, and exact description.

This invention relates to flying-machines, 10 the primary object being to provide means for maintaining the equilibrium of such machines when in the air. It is well known that such a device is a great desideratum in the science of aerial navigation and that the lack 15 of an efficient device for performing this function has been one of the greatest obstacles in the way of successful flight. The great difficulty in preserving equilibrium is due mainly to the variability of air-currents in direction 20 and force. If an element can be introduced in the machine that will resist a change in its level or plane to such an extent as to maintain equilibrium or to allow time for making the necessary shifting of ballast, such an element 25 will constitute what may be regarded as the missing link in flying machinery. The resistance which a rotating body offers to any change in the plane of its rotation is best illustrated in the fly-wheel, in which the weight 30 is chiefly in the rim. For this reason I make a fly-wheel, with means for rotating it, the fundamental element in the flying-machine, and I believe that such a rotating fly-wheel offers the best, if not the only, purely mechanical 35 means at present attainable for maintaining automatically the equilibrium of a flying-machine.

Although up to the present time purely mechanical flight from a practical standpoint 40 has not been accomplished, it is evident from the result of recent experiments of prominent scientists in this art that flight by purely mechanical means will very soon be achieved.

It is the object of my invention to provide 45 a means for maintaining automatically the equilibrium of a flying-machine of any character; but in order to combine my invention with what is at present understood to be an operative flying-machine I have herein described it in connection with that class of flying-machines which utilize a gas-field; but in-

asmuch as the invention *per se* has nothing whatever to do with the lifting, propelling, or steering apparatus of the machine, but is merely a means for maintaining the equilibrium 55 of any machine capable of sustaining itself in the air, it is obvious that my invention is not limited to a machine that comprehends a gas-field, but will be applicable to a purely mechanical flying-machine whenever 60 such is produced.

In the accompanying drawings, forming a part of this application, Figure 1 is a side elevation of the flying-machine equipped with my improvements. Fig. 2 is a plan of the 65 bottom of the machine with the car removed.

Referring to the drawings by letter, A represents a combined storage-tank and frame. It is a tubular structure in the form of a ring and adapted to receive air or gas under pressure, to be utilized as a power for propelling and steering the machine. This frame supports beneath it a basket or car B for passengers or freight, to which it is connected by suitable braces and supports b. To the top 70 of the frame is rigidly attached a closed balloon C, preferably of the shape shown and adapted to receive a gas lighter than the atmosphere. In the middle of the frame A is placed a short vertical shaft a, upon which 75 of the frame is rigidly attached a closed balloon C, preferably of the shape shown and adapted to receive a gas lighter than the atmosphere. In the middle of the frame A is placed a short vertical shaft a, upon which 80 of the frame is rigidly attached a closed balloon C, preferably of the shape shown and adapted to receive a gas lighter than the atmosphere. In the middle of the frame A is placed a short vertical shaft a, upon which 85 of the frame is rigidly attached a closed balloon C, preferably of the shape shown and adapted to receive a gas lighter than the atmosphere. In the middle of the frame A is placed a short vertical shaft a, upon which 90 of the frame is rigidly attached a closed balloon C, preferably of the shape shown and adapted to receive a gas lighter than the atmosphere. In the middle of the frame A is placed a short vertical shaft a, upon which 95 of the frame is rigidly attached a closed balloon C, preferably of the shape shown and adapted to receive a gas lighter than the atmosphere.

At d is a propeller by which the machine may be driven forward or backward, it being 90 rotated by an air or gas engine d', supplied with power from tank A.

At e is a steering-propeller which by rotating it in one or the other direction will throw the end of the machine to the right or 95 left.

The balance-wheel a' is the feature constituting my invention. This when in rotation resists any force that tends to swerve, tilt, or otherwise throw out of balance the machine, and therefore furnishes a means for 100 maintaining equilibrium. The wheel should

be of comparatively large diameter and may be set in a vertical plane or at an angle. It is to be driven constantly during flight.

Two or more balance-wheels may be used 5 and advantage taken of the aggregate influence.

I have shown the fly-wheel as driven by an independent engine *c*, and it is essential for practical work that it should be so driven, 10 or at all events by power independently applied. The fly-wheel should not be on the same shaft with a propeller, and the construction should be such that the fly-wheel may be kept in motion while the ship is poised in air.

Having thus described my invention, I 15 claim—

In a flying-machine, the combination of a fly-wheel mounted to rotate independently of other machinery and a motor adapted to drive the same, substantially as and for the purpose set forth.

In testimony whereof I subscribe my signature in presence of two witnesses.

JAMES RICHARDSON.
